UNITED STATES PATENT OFFICE.

WILLIAM A. DROWN, OF ABINGTON, PENNSYLVANIA.

DESIGN FOR AN UMBRELLA OR PARASOL COVER.

SPECIFICATION forming part of Design No. 12,569, dated November 15, 1881.

Application filed October 7, 1881. Term of patent 14 years.

To all whom it may concern:

Be it known that I, WILLIAM A. DROWN, a citizen of the United States, residing in Abington, Montgomery county, Pennsylvania, have 5 invented a new and original Design for an Umbrella or Parasol Cover, of which the following is a specification.

My design for umbrella and parasol covers is fully shown in the accompanying drawings, 10 in which—

Figure 1 represents the cover as applied to the umbrella or parasol, and Fig. 2 an enlarged view of part of the cover.

The design comprises a corded band, *a*, of a 15 character clearly shown in Fig. 2, said band extending transversely across each segment of the cover, parallel with and near the lower end of said segment, so that when the complete cover is applied to the frame of the umbrella 20 or parasol, as shown in Fig. 1, the band of one

segment will coincide with those of the adjoining segments, thus forming a corded band extending completely around the umbrella or parasol parallel with and a short distance from the outer edge of the cover.

I do not desire to claim, broadly, an umbrella-cover having a band near the edge; but

I claim—

The within-described design for an umbrella or parasol cover or cover-segment, said design 30 comprising the corded band *a*, as shown and described.

In testimony whereof I have signed my name to this specification in the presence of two subscribing witnesses.

WM. A. DROWN.
